UNITED STATES PATENT OFFICE

2,382,576

DISPENSING UNIT

Charles F. Pease, Long Beach, Calif.

Application November 7, 1942, Serial No. 464,838

4 Claims. (Cl. 312—56)

My invention relates to improvements in vending machines of that type which is particularly adapted for dispensing picture post cards, stamped envelopes and articles of similar type, and which is further adapted, when desired to be operated through the medium of any suitable coin controlled actuating means. This application is a continuation in part of my companion applications, Serial Number 364,621, filed November 7, 1940 which has issued as Patent No. 2,309,008 on January 19, 1943, and Serial Number 370,272, filed December 16, 1940 which has issued as Patent No. 2,353,496 on July 11, 1944.

A particular feature in the present application which is broadly incorporated into the construction disclosed in said companion applications is that of displaying the article about to be discharged by the machine in full view so that the vendee can see before operating the machine what is next to be dispensed.

Among objects of the invention is maximum simplicity and effective construction which permits ready fabrication, coupled with dependability in operation, whereby the machine will successively dispense articles of the types above stated. Among further objects is the production of a vending machine of the type stated which can be easily and successfully incorporated into a multiple unit vending apparatus to be operated by one or more coin controlled instrumentalities.

In the accompanying drawings forming part of this specification, Fig. 1 is a front elevation of my improved vending machine when disassociated from the actuator by which the machine is manually operated; Fig. 2 is a back elevational view of the structure shown in Fig. 1; Fig. 3 is a bottom plan of the structure shown in Fig. 1; Fig. 4 is a section taken approximately on line 4—4 of Fig. 3; and Fig. 5 is a side elevation showing an actuator applied for operating my improved vending machine, the actuator being suitably coin controlled and a portion only of the vending machine being shown.

My improved vending machine has an upwardly and rearwardly slightly inclining skeleton frame A, in which there is a sight opening 10 closed by an upwardly and rearwardly reclining glass or other transparent plate 11, said frame being adapted to be incorporated into a panel indicated by 12 in Fig. 3, of a multiple vending machine structure, whereby a number of different articles, each dispensed by a separate unit can be controlled from a single or a plurality of coin operated elements. The sight opening is

of such shape and size as will display the article to be dispensed, the structure shown having a rectangular opening and being adapted to dispense articles such as picture post cards, indicated by B. The side edges of the face frame have laterally extending flanges 13, by which said frame is supported on the panel structure. Said frame also has upwardly and rearwardly extending flanges 14 at the opposite sides of the sight opening, merging downwardly into an upwardly and rearwardly extending supporting lip 15, which has a pair of rearwardly extending stop shoulders 16 on its rearward end. The lip 15 movably supports a downwardly and forwardly slanting gate 17 back of the sight opening upon which a stack of the cards or other articles to be dispensed are supported while standing on edge with the face of the forward and bottom member resting against the transparent plate 11. The gate is fastened to the lip piece 15 and is adjusted longitudinally relative to the back of the transparent plate by the sets of screws 18 and 19 and lock screws 19'. By adjusting the gate the width of the gate or slot opening between the lower end of the gate and transparent plate 11 can be varied to dispense post cards or other sheets of firm material of different thicknesses.

The screws 19' have slotted connections upwardly through the stop shoulder 16 as shown in Figs. 3 and 4 and have threaded connection with the lower side of the gate 17 so as to assist in guiding the gate longitudinally and retaining the latter upon the surface of the upwardly and rearwardly slanting lip 15. The gate 17 is adjusted longitudinally in a forward direction upon the lip 15 to contract the gateway D by the screws 18, the shanks of which engage freely through the flanged rearward end 17' of the gate and are threadedly engaged with the shoulder elements 16 as indicated in Fig. 3. Thus when the screws 18 are tightened the gate is adjusted to regulate the width of the gateway D. The screws 19 are threadedly engaged through the flanged rearward end 17' of the gate and the forward ends of their shanks bear against the rearward faces of the shoulder elements so as to either withdraw the gate and widen the gate opening D or tighten the hold of the adjusting screws 18 and prevent the latter from loosening. To cause rearward adjustment of the gate the screws 18 are loosened and the companion screws 19 are tightened.

The gate is adapted to slide longitudinally on said lip when adjusted and is provided with an

upwardly and rearwardly extending back stop 20 by which the follower C to be hereinafter described is removably held. A pair of vertical side guard plates 21 between which the follower slides are secured rigidly to the supporting flanges 14 by screws 22 and lugs 16 or other suitable means. The gate 17 is slidably held below the lower ends of the guard plates 21 on the supporting lip 15.

The vertical side plates 21, gate 17, follower C and transparent plate 11 in the sight opening, form a magazine in which a pack of post cards or other articles of a similar type such as B are closely packed against the inner face of the transparent plate while resting by their lower edges upon the surface of the slanting gate 17. The lower edge of the gate cooperates with the inner face of the transparent plate 11 to produce a gateway D, of a width suitable to permit a single post card or other article being dispensed from the machine at a time. As each article is dispensed it is projected downwardly below the machine so that the vendee can grasp and remove the same.

The follower C is guided and manually manipulated by the shaft 25 which extends rearwardly and slides in the longitudinal hole 26 in the upper end of the support 20, while it is retained in parallel relation to the back of the transparent plate 11. A helical expansion spring 27, threaded loosely over the shaft 25 and interposed between the support 20 and the follower, presses the follower plate lightly toward the transparent plate 11 and holds the pack of cards or other articles stacked in the magazine in readiness to be dispensed one at a time through the gateway D. The rearward end of shaft 25 has a handle 28 by which the follower can be removed or adjusted to place a fresh supply of cards or other articles to be dispensed in the magazine. The back of the follower C has engaging lugs 29 by which the inner end of spring 27 is fastened thereto and held in operative position.

The means by which the cards are successively ejected from the stack of cards held in the machine consists of an ejector E, resembling a thin flat plunger removably mounted upon a reciprocating carriage 30 by the clip 31. This carriage slides vertically upon a pair of depending guide rods 32 and 33 which are rigidly secured to the inwardly projecting bosses 34 on the upper portion of the face frame A. One end of the carriage 30 has a depending yoke 35 which is guided on rod 33 and contains an expansion spring 36, threaded over said rod. The lower end of the expansion spring is attached at 37 to said rod and its upper end presses against the upper portion of the yoke to raise the carriage and the ejector E into superior position above the pack of cards retained in the holding means as shown in Figs. 2 and 4, coincident with the sight opening. The bosses 34 function as back stops for limiting the upward movement of the carriage and its ejector. In raised position the ejector is poised above the upper edge of the innermost post card or other article to be dispensed on the bottom of the pack and being of a thickness substantially corresponding with the thickness of said card and the stroke thereof being relatively short it is adapted to project the card partway down through the gateway.

The forwardly and downwardly slanting floor of the gate assists in feeding the stack of cards forwardly without sticking together or jamming

the machine. Also slightly slanting the transparent plate and follower C upwardly and rearwardly also assists in the same manner to prevent the cards from sticking together or jamming the machine.

The carriage is driven downwardly to reciprocate the ejector E by the operating rod 40, upon the lower end of which is the drive antifriction pinion 41. To drive the operating rod 40 a suitable actuator such as F (see Fig. 5) is provided. This actuator is adapted to be controlled by suitable coin controlled operating mechanism, the pull rod 42 of which is shown. The actuator consists of a suitable frame 43, which may be mounted upon a portion of the cabinet such as 12, containing the vending apparatus. Reciprocable in and out of the frame 43 is a hand operable pull rod 44, which fixedly supports a collet block 45, on the lower side of which is a boss 46 and on the upper side a longitudinal series of ratchet teeth 47. The frame 43 has a rigid depending inner arm 48 to the lower extending portion of which is pivoted at 49 a forwardly extending swinging lever 50, the free end of which is linked to the boss 46 so that as the hand operable pull rod 44 is reciprocated longitudinally, the drive lever is swung up and down. An expansion spring 51 is threaded over the shank of pull rod 44, between the outer portion of the frame 43 and the collet block 45. This spring permits the pull rod 44 to be drawn outwardly and to swing the lever 50 downwardly and serves to return the pull rod inwardly and swing the lever 50 back into raised position. The lever 50 is provided with a pair of shoulders 52 spaced apart sufficiently to admit and engage the anti-friction pinion roller 41 on the operating thrust arm 40. In mounting the parts on the cabinet the actuator F is positioned so that the shoulders 52 cooperate with the pinion 41 and cause functioning of the vending apparatus in the manner stated. The drive lever 50 is shown connected by a link 53 and pivoted clamp block 54 to the coin control rod 42, by which the operation of the dispensing unit actuator F may be controlled in the usual manner by depositing a coin in a slot.

To produce a complete forward and return stroke during each complete operation of the machine a double acting spring controlled pawl 55 is freely pivoted at 56 on the frame 43 so as to cooperate with the ratchet teeth 47 on the sliding collet block 45 as the pull rod 44 is reciprocated in either direction. This pawl is retained in normal position out of contact with the ratchet teeth 47 when the pull rod 44 is in receded position by the vertically poised helical retractile spring 57. As the pull rod is drawn outwardly the pawl sweeps over the teeth and automatically acts as a ratchet stop to prevent any return movement until a complete stroke has been made and vice versa, after complete withdrawal movement has been made and the pull rod retracts into the machine the pawl again sweeps over the teeth and prevents reverse movement until a complete backward stroke has been completed. In this manner, jamming by improper operation and milking of the machine are prevented. The forwardly and downwardly slanting gate in cooperation with the slanting follower and transparent plate assists in automatically feeding the pack of post cards or other articles being dispensed, downwardly, partly by gravity and by the aid of the spring 27 from the magazine into a position whereby the low-

ermost card coincides with the gate opening and the ejector engages its upper edge without disturbing the card or cards immediately following in the magazine, thus effectively feeding the cards successively from the machine. The gate also being adjustable to regulate the width of the gate opening enables the machine to be set to feed post cards or other articles of any desired thickness. The ejector E also being replaceable upon the carriage 30 by removing the clip 31, permits the application of another ejector of a thickness corresponding with the thickness of any card or article being dispensed. By holding the stack of cards with the lowermost card flat against the transparent plate 11, and directly above the gate opening, the cards are discharged successively without jamming or mutilating by the ejector when the latter is reciprocated. This result is partly due to the smooth anti-friction surface offered by the transparent plate and the absence of corners and sharp edges which might otherwise tend to obstruct smooth operation.

In accordance with the patent statutes, I have described the principles of operation of my invention, together with the apparatus which I now consider to represent the best embodiment thereof, but I desire to have it understood that the construction shown is only illustrative and that the invention can be carried out by other means and applied to uses other than those above set forth within the spirit thereof and within the scope of the following claims.

I claim:

1. A dispensing unit, comprising, a face frame having an upwardly extending sight opening through which an article about to be dispensed is displayed, upwardly extending side guards at the sides of said sight opening and a support extending upwardly and rearwardly from near the lower portion of said frame and spaced below the lower ends of said guards, a transparent plate in said sight opening, a forwardly and downwardly inclined gate for supporting a stack of cards to be dispensed while standing on edge with the face of the lowermost card pressed against said plate, said gate being slidably disposed below the lower ends of said side guards upon said support with its lower inner end spaced back of the inner surface of said transparent plate to provide a gate opening for the downward discharge of the lowermost card of said stack, a carriage reciprocable downwardly against spring tension on the back of said face frame, an ejector blade depending from said carriage, substantially corresponding with the thickness of the cards, normally poised above the inner-

most card of the stack and cooperating with said gate opening to discharge the lowermost card from the stack downwardly through the gate opening, and actuating means by which the carriage and said ejector are reciprocated.

2. In a structure as defined in claim 1, the gate having an upwardly extending back stop, a spring pressed follower plate forward of said stop and urged against the stack of cards to hold the cards against the transparent plate, and a supporting shaft extending rearwardly from said follower and movably held by said back stop.

3. In a structure as defined in claim 1, the gate having an upwardly extending back stop on its rearward end, a follower plate forward of said stop adapted to urge the stack of cards against the transparent plate, a supporting shaft extending rearwardly from the follower plate and movably held by said stop and a helical expansion spring encircling said shaft and compressed between said stop and plate to urge the latter forwardly against the stack of cards, said follower plate having means for engaging the inner end of said spring to hold the latter in place thereon.

4. A dispensing unit, comprising, a face frame having an upwardly extending sight opening, a supporting member extending upwardly and rearwardly from its lower portion and a pair of side guards spaced laterally apart and having their lower ends terminating above said supporting member, a transparent plate in said sight opening, a gate reciprocably disposed upon said supporting member, said gate being adapted to support a stack of cards to be dispensed while standing on edge with the face of the lowermost card resting against said transparent plate and said gate having its lower end juxtaposed to and cooperating directly with the inner surface of said transparent plate to produce a smooth gate passageway for the uninterrupted discharge of the lower end of each of the lowermost cards of said stack, adjusters between said supporting member and the opposite ends of said gate for regulating the size of the gate opening, downwardly extending guides on the opposite ends of said face frame, a carriage having limited reciprocable movement downwardly upon said guides, an ejector blade mounted upon said carriage above said gate opening substantially corresponding with the thickness of the cards to be dispensed and having limited movement to engage the lowermost card and discharge its lower end from the stack downwardly through the gate opening, and means for imparting limited reciprocable movement to said carriage.

CHARLES F. PEASE.
